RAILWAY JOURNAL LUBRICATOR PUMP

James J. Hennessy, Montclair, N. J.

Application June 1, 1942, Serial No. 445,299

8 Claims. (Cl. 308—84).

The invention relates to lubricators for railway journals or the like in which the mechanical pump is actuated by the play of the journal in the journal box longitudinally of the journal.

The restricted space between the bottom of the journal and the bottom of the box usually requires that the box be jacked up from the journal, the journal bearing and wedge removed, and the box lowered directly onto the journal before the lubricator device could be applied or removed.

One of the problems attending the installation and use of such a pump in the ordinary, outside bearing, A. A. R. standard journal box, in general use on railway rolling stock, particularly in the smaller sizes of boxes, is the insertion and removal of the lubricator through the open end of the box and beneath the journal.

The main object of the present invention is to facilitate the insertion and removal of a lubricator device into and from the space beneath the journal while it is in the journal box.

Another object is to securely position the pump in the box when the pump is in operating position without affecting the removability of the pump when desired.

Patents No. 1,948,297 and 2,182,205 have the same general object and are satisfactory in some installations but each of these devices have certain limitations. In the first of these patents, a bell crank is pivoted on the pump body at a point beneath the journal with one arm engaging the end of the journal and the other arm engaging the pump piston at a point beneath the journal. This arrangement necessitates the piston engaging arm being of such short length that its effective length is varied greatly during the stroke and it must slide over the end of the pump plunger. This undesirable limitation is particularly accented if the installation is in a small size journal box. In the second of these patents, the pump is spring supported immediately beneath the journal and is actuated by a slideable journal engaging element and depends for its intake upon a hinged depending arm. In this pump the plunger is not actuated by the preferred pivoted lever device characteristic of the other pump and the complete structure is more complicated than desirable.

It is an additional object of the present invention to secure an effective leverage arrangement, positioned beyond the end of the journal, for actuating a pump plunger positioned in a pump body beneath the journal.

These general objects and other detail objects

as will be described below are attained by the structures illustrated in the accompanying drawing in which—

Figure 1 is a longitudinal vertical section through the lower portion of an A. A. R. (American Association of Railroads) journal box mounted on an A. A. R. journal and to which the present lubricating device, including a suitable distributor, has been applied, and is taken along the line 1—1 of Figure 2.

Figure 2 is a top view of the pump body and its operating mechanism, the box walls being shown in section and the journal indicated in broken lines.

Figure 3 is a vertical transverse section through the box and looking at the forward end of the lubricator with some of the details sectioned to better illustrate the construction.

The journal 4 mounts the usual bearing and wedge (not shown) upon which the box 4 is carried and the latter is of the usual A. A. R. construction with upright side walls 5 and a bottom wall 6 rounded upwardly at the front of the box. The front end of the box has the usual opening 7 provided with a door (not shown) and the rear end of the box has the usual opening 8 and is equipped with a suitable dust guard (not shown).

All of the above elements are of familiar construction and in themselves do not constitute the present invention. The lubricating device consists generally of two parts, a pump unit 10 and a distributor unit 11. The pump unit includes a body casting 13 arranged to rest upon the bottom of the box and having parallel bores 15 forming the pump cylinders. Individual valved passageways (not shown) lead from cylinders 15 to a common outlet 17 near the inner end of body 13.

Each piston 20 projects forwardly beyond the pump body and is counterbored to receive a push rod 22 terminating in a hook 23. Projecting diagonally forwardly and upwardly from the forward end of the pump body are ears 24, the outer ends of which contact with the upturned portion of bottom wall 6 to hold the pump against movement to the left (Figures 1 and 2). Levers 26 are pivoted at 28 to the respective ears and the inner end of each lever is apertured to receive the hook 23 of the corresponding push rod 22. Each ear 24 is drilled substantially parallel to the plane of the corresponding lever 26 to form a bearing for the lower end or fulcrum 28 of a lever 30, the upper end of which terminates in a ball-like contact element 32 arranged to

bear against the outer end of journal 1 and to be moved by the latter towards the forward end of the box when the journal shifts towards the end of the box and, in so doing, to engage the outer end of the corresponding lever 26 and rotate the latter so that its inner end thrusts rod 22 and the piston inwardly of the pump body.

The outer end of each piston 20 is provided with a collar 33. The outer end of the pump body is counterbored at 34. A coiled spring 35 encircling the piston is seated at its opposite ends against collar 33 and the inner end of counterbore 34. Upon movement of the journal to the right (Figures 1 and 2), springs 35 return the pistons and levers 26 and 30 to their original positions, maintaining the contact between elements 32 and the end of the journal. The interior structure of the pump corresponds to that of my copending application, Serial No. 435,769, filed March 23, 1942, and in itself does not constitute the present invention.

A U-shaped holding plate 40 fits around the main portion of the pump body, having recesses 41 to receive body lugs 42, and extends between the box side walls and is provided with down-turned lips 43 resting on the box bottom wall and with a tail piece 44 extending over the rear end of the pump body and rearwardly therefrom to the box rear wall. Preferably the lower edges of lips 43 and the end of piece 44 are welded to the box at W so that plate 40 positions the pump transversely and longitudinally of the box.

The underside of the pump body immediately beneath intake valves 45 is elevated from the box wall by rib-like elements 37 to provide clearance for the flow of oil to the intake, and a screen 46 overlies the adjacent portion of the pump to prevent dirt and other foreign matter from entering the intake.

The articulated distributor is of the type illustrated in my Patent 2,272,199, issued February 10, 1942, and in my application, Serial No. 409,-761, filed September 6, 1941, and it is supported by the spherical lower end of its arm 47 in the spherical seat 48 in the pump body.

From the above description and the accompanying drawing it will be seen that the pump unit 10 is relatively short and is readily inserted through the box opening 7 into its functioning position beneath the journal and is held firmly against shifting from its functioning position until it is positively withdrawn.

The pump unit and the distributor unit may be inserted beneath the journal separately and there assembled by inserting the lower end of arm 47 in seat 48.

It will be understood that the lower portion of the box is provided with a supply of oil and that the pump is operated by the reciprocation of the journal in the box, each movement of the journal to the right resulting in the spring actuation of the pump pistons outwardly to draw oil through intake valves 45 and each movement of the journal in the opposite direction moving levers 30 and 26 to thrust pistons 20 inwardly to discharge oil through outlet 17 in the lower portion of distributor arm 47 whereby lubricant is supplied to distributor plate 50 during the operation of the vehicle.

The compound leverage arrangement positioned outwardly of the end of the journal facilitates the provision of desired piston movement to accommodate different journal movements, different densities of oil and other conditions such as size of the journal, the rods on the jour-

nal, climate, etc. When the box is jacked up to change the bearing, the lower edge of the journal collar C may contact lugs 49 on the top of the pump body, in which case the thrust will be transferred through the latter and through forward ribs 37 directly to the bottom wall of the box without injury to the pump. Lugs 51 on ears 24 oppose the adjacent edges of levers 26 and limit the movement of the outer ends of these levers away from the pump body and thereby prevent the falling over outwardly of the upright levers 30 when the pump is being applied to or removed from its operating position in the box. Lugs 52 on ears 24 oppose the lower portions of levers 30 and prevent the latter from falling over inwardly under similar conditions.

The compound leverage arrangement makes it possible to locate the fulcrums of the journal-engaging levers 30 adjacent to the box bottom wall but spaced transversely of the box from the pump cylinders and pistons which must be immediately adjacent the lowermost portion of the box, which constitutes an oil sump. Hence the pump body may be made very shallow and its projection outwardly of the plane of the end of the journal may be minimized, thus facilitating the insertion and removal of the pump through the end of the box into and out from the space beneath the journal. Any desired reciprocal movement of the pistons may be obtained by shifting the fulcrums for piston-engaging levers 26, and this change in the lever arms will not require any increase in the depth, width or length of the pump body.

All the parts are easily manufactured and readily assembled and there is thus provided a durable, economical structure for the intended purpose.

What is claimed is:

1. In a railway axle journal lubricator of the type operated by the axial play of the journal in the journal box, an elongated pump body adapted to lie along the longitudinal center of the bottom of the box and provided with a cylinder and a piston, a piston-actuating lever pivoted on the pump body and extending laterally from its piston-actuating end towards the side of the box, and another lever fulcrumed on the pump body and extending upwardly therefrom past and acting on the outer end of said first-mentioned lever and having a journal-opposing upper terminus.

2. A structure as described in claim 1 in which the piston-actuating lever is inclined upwardly from its inner piston-actuating end and the journal-opposing lever is inclined inwardly from the end of the other lever.

3. Structure as described in claim 1 which comprises duplicate cylinders and pistons and operating levers therefor disposed at opposite sides of the longitudinal center line of the structure with the piston-actuating levers extending in opposite directions from the center of the structure.

4. Structure as described in claim 1 in which the forward portion of the pump body is provided with an ear inclined upwardly and laterally from the cylinder-forming section and the levers are fulcrumed on said ear at points spaced laterally from the cylinders and pistons.

5. Structure as described in claim 1 in which the portion of the journal-opposing lever above its contact with the piston-actuating lever is offset outwardly of the end of the pump body to permit the end of an associated journal to project over the fulcrum of the journal-opposing lever.

6. In a railway axle journal lubricator, a pump body including a cylinder, a piston reciprocable in the cylinder, a spring associated with said cylinder and body for thrusting the piston in its outward movement in said cylinder, said piston having an axial bore in its outer end, a piston-actuating lever pivoted on said body with one end disposed in alignment with the piston, a push rod of substantially smaller diameter than said bore with one end pivotally seated in the inner end of said bore and with its other end engaged by said lever, and a cooperating lever pivoted on said body with one end arranged to contact the end of an axle journal to which the device is applied and with another part of the cooperating lever arranged to operatively engage said first-mentioned lever to actuate the latter against said spring by the shifting of the journal relative to the pump body.
7. In a railway axle journal lubricator, a pump body including a cylinder, a piston reciprocable in the cylinder and having a portion projecting outwardly therefrom, said body having a bore of substantially larger diameter than said piston surrounding the outwardly projecting portion of the latter, a spring received in said bore and engaging said piston portion to thrust the same outwardly of the cylinder, said piston portion having an outwardly opening bore, a push rod
- of substantially smaller diameter than said piston bore received in said bore and projecting outwardly therefrom, and a piston-actuating lever disposed to engage the outer end of said rod and operable to move the piston inwardly of the cylinder against the thrust of said spring, and a cooperating lever pivoted on said body with one end arranged to contact the end of an axle journal to which the device is applied and with another part of the cooperating lever arranged to operatively engage said first-mentioned lever to actuate the latter against said spring by the shifting of the journal relative to the pump body.
8. In a journal lubricator of the class described, a pump body member having a pair of pump cylinders spaced transversely from the longitudinal center line of the lubricator, pistons in said cylinders, and means for operating the piston at one side of said center line comprising a substantially horizontally disposed lever fulcrumed on said body member with one end actuating said piston, and a substantially upright lever fulcrumed on said body member with one end acting on the other end of said first-mentioned lever and with its other end opposing the end of the journal at one side of said center line.
